METHOD OF GRINDING WORKPIECES

Clement Booth and Sol Einstein, Cincinnati, Ohio, assignors, by mesne assignments, to The Heald Machine Company, Worcester, Mass., a corporation of Massachusetts

Application May 19, 1930, Serial No. 453,540

3 Claims. (Cl. 51—278)

This invention relates to improvements in grinding and has particular reference to an improved process for production of tubular articles such as the bearing rings or races for ball bearings.

Prior to the present invention, it has been the customary practice in the production of articles such as inner rings or races for ball bearings, and like articles, to mount the work piece in a suitable rotating chuck, or the like, and to grind the inner or seating face to the desired cylindrical form which might or might not be concentric with the general outer surface of the work piece depending on the accuracy of the chuck members. These inaccuracies are normally of such degree that if a work piece be slightly incorrect as to size it is commercially impossible to replace the same in the chuck for regrinding in a position which would be concentric with that initially occupied. Thus, unless the work piece be suitably undersize, it is impossible to regrind to a true circle not having high and low spots.

This grinding of the inner surface of the race ring having been performed, the standard practice involves mounting the article on a suitable holder or mandrel, and rotating the same while so mounted in opposition to a grinding wheel for generating the ball seat or race way in the outer face. The concentricity of the race way with the inner ground seat, operative to determine the position of the bearing as a whole when in use, is therefore dependent on the interfitting of the ring and mandrel, on the mounting of the mandrel itself as to concentricity, and in addition on any looseness or play of supporting portions of the machine in engagement with the mandrel. As a result, accurate production of these parts, to within the desired fraction of a thousandth of an inch, these limitations being desirable in machining operations of the present day, has been extremely difficult, if not impossible on a commercial basis.

Due to the fact that the ungrooved portions of the outer surface of the inner ring are a non-functioning surface as respects the bearing when in use, no particular attention has been given to this surface.

The primary object of the present invention is the provision of a novel process for the production of articles, such as these inner races, in which the inaccuracies as to concentricity will be reduced to a minimum, and at the same time a process in which either the inner surface or the outer race way for example may be accurately, correctively reground, if the inner surface be

undersize or the outer surface oversize, and true concentricity will be accurately maintained both during the original grinding and during any subsequent corrective actions thereon.

A further object of the invention is the provision of an improved process which will eliminate the interdependence of the inner and outer operative surfaces of the work piece and will provide a common position determinator for the work piece during production of both of said surfaces.

An additional object is the provision of a process for production of work pieces of the character above set forth, of maximum accuracy capable of interchangeable employment, and which will be effective to eliminate the dependence of the work pieces for accuracy on adjustment and engagement of chucks and centers, or general spring or play in the supporting portion of the grinding machine.

According to the present invention, the process is carried out by supporting the workpiece for rotation on a preformed cylindrical surface of said workpiece and producing a surface on said workpiece while the latter is supported and rotated on said preformed surface and simultaneously or subsequently producing one or more additional surfaces on said workpiece while the latter is supported for rotation on the same preformed surface. In this manner, each of the surfaces produced is concentric to the preformed surface and accordingly the surfaces produced are concentric to each other. By this arrangement, the plurality of concentric surfaces may be produced while the workpiece is mounted in a single supporting member or each surface may be produced by mounting of the workpiece in separate supporting members. Since the workpiece, however, is rotated on a preformed cylindrical surface during the cutting of each of the plurality of concentric surfaces, the surfaces produced will be entirely concentric.

To facilitate an understanding of the process in question a series of diagrams thereof are illustrated in the appended drawing, in which

Figure 1 is a sectional view of a double race way ball bearing.

Figure 2 is an end view of a work piece prior to grinding the surface, inequalities being shown in exaggerated form for ease of comparison with the subsequent views.

Figure 3 is a similar view of the workpiece after the first operation has been performed thereon.

Figure 4 is a similar view of the workpiece after another operation has been performed thereon.

Figure 5 is a similar view of the completed work-piece.

Figure 6 is a diagrammatic view, in elevation, to bring out the manner of performance of the 5 first step in the process.

Figures 7 and 8 are diagrammatic views, respectively in elevation and in plan showing the performance of the step in the process as indicated by Figure 4, and

10 Figure 9 is a diagrammatic view in elevation showing a structure for performing the final step in the grinding of a workpiece.

Figure 10 is a diagrammatic plan view of the structure of Figure 9.

15 In its original form the work piece 10 is in the form of a ring having an unfinished outer surface 12 and an unfinished inner surface 13, with a central aperture 14. The inner wall 13 in the finished article becomes a finished surface 20 13a, adapted for tight fitting engagement with a shaft 15, for example, while the outer surface 12 is intended to be provided with the race ways as at 16 and 17, for example, to receive the balls 18 of the complete bearing structure. It is essential 25 in the finished article, that the race ways 16 and 17 be reduced to precisely the correct diameter or size and also that they be precisely concentric to the surface 13a, and thus, in turn, concentric to the axis of revolution of shaft 15 to eliminate 30 eccentric or gyratory movement of the shaft and consequent vibration when the bearing is put into operation.

It will be noted by reference to Figure 1 that 35 the outer surface 12 of the inner ring 10 has no functional purpose as a surface, there being a suitable clearance between it and the inner surface of the outer bearing ring 19. Consequently in the past, no particular attention has been given to the manner in which this surface was 40 machined or finished and no attempt made to establish any definite relationship between said surface and the operative faces of the bearing ring.

In the present process of manufacture, the first 45 step consists in the initial formation of a definite cylindrical outer surface on the member 10, preferably by precision grinding on a centerless grinder, as shown in Fig. 6, to the end that the work piece will be a true circle in cross section and 50 round within a fractional thousandth of an inch. Obviously, the first step may be eliminated when the workpiece is provided with a preformed surface of revolution which is concentric to the desired surfaces to be produced on the workpiece.

55 After this outer surface has been properly formed, said surface is used as the position determinate for the work during the formation of a multiplicity of surfaces concentric thereto; in the construction shown, these surfaces comprise the 60 inner cylindrical or conical surface or seat 13a, and the groove, grooves, or race ways 16 and 17 for the circumscribing ball or roller bearing members of the completed bearing. By utilization of the first or preformed surface 12 in a manner 65 similar to that employed in centerless grinding of cylindrical articles, that is, namely with the surface of the workpiece resting on a suitable support such as a work rest blade 20, and at the same time in engagement with a second throat 70 forming member which may assume, for example, the form of a driven friction disc or regulating wheel 21, the use of chucks, or like holding members, is eliminated. This is a pronounced 75 advantage, since, as above stated, it is found impossible in commercial chucks, after having

withdrawn a piece which has been internally ground, to reinsert the piece in the same or another chuck and just spark out the interior with the grinding wheel, due to the fact that there will be a slight difference in the orbit or path of the movement of the piece when rechucked, so that it will not revolve about the identical axis on which its surface was previously produced. While this variation may be of the nature of a thousandth of an inch displacement of the axis, or even less, 10 when considered as an error in diameter it is several times the allowable commercial limit of error in production, and of a degree sufficient to seriously impair the accuracy and life of the bearing, and the piece if reground in this manner 15 from slightly undersize when completed, to the newly determined circle will generally be appreciably oversize.

The process contemplates the utilization of the surface 12 in the manner above pointed out during 20 the formation of the central aperture or seat 13a by a grinding operation, as indicated in Figs. 7 and 8, said surface being produced while the workpiece is supported and rotated on the first or preformed surface 12. Obviously, by such rotation of the workpiece as the surface 13a is formed, said surface is concentric to the surface 12.

Likewise, the process contemplates the corresponding utilization of a work rest member 20a 30 and a positioning member 21a for engagement with the preformed periphery 12 of the work to determine its position and axis of rotation during formation of the race ways. In this manner, the race ways and the bore will be accurately concentric one with the other, and either can be correctively reground or varied as desired without in any wise affecting their relative concentricity. This again has been impossible in the past, where the exterior grinding has been performed with the work held on chucks, mandrels, or other centering devices engaging the interior surface while the race was being formed.

In the carrying out of the process therefore the work is first suitably ground, as for example, in a centerless grinder such as diagrammatically indicated in Figure 6, to produce the truly cylindrical outer surface 12. The succeeding two steps of the process can then be alternatively performed, for example, first mounting the work as shown 45 in Figures 7 and 8. In these figures use is preferably made of a supplemental pressure roller 22 to maintain proper two-point contact of the members 20 and 21 with the periphery of the work and insure its proper rotation. Means such as 50 the stop 23 may be utilized to restrict axial movement of the work piece with respect to the supporting and driving devices therefor. An internal grinding wheel 24 is utilized, operating in definite relation to the exterior and preformed surface 55 of the work and preferably in opposition to the rotating friction member 21, which has a rigid or non-yielding surface, opposing yielding of the work under cutting or feeding pressure. While the work is restrained against independent axial movement, there is preferably effected an axial movement relatively between the grinding wheel and its supporting unit, so that the grinding wheel 60 properly traverses the inner surface of the work, producing a smooth finish thereon without 65 grooves or scratches.

In the formation of the race way or race ways, the work is again supported, as indicated in Figures 9 and 10, on its outer periphery by engagement of the members 20a and 21a therewith, and 75

preferably restrained against axial movement in either direction with respect thereto, as by the stops 23a and 23b. Likewise, a pressure roll, such as 22a, may be utilized to firmly press the 5 work into the two-point supporting throat. While so held and rotated, it is exteriorly engaged, as by the grinding wheel 26 having a formed peripheral surface for production of the race way. This wheel may be mounted on a 10 swivel support as at 27, whose axis extends parallel with a tangent to the surface of the work piece at the point of engagement of wheel 26 therewith. Since the swivel support 27 has a predetermined position relative to the base of 15 the machine and in predetermined position relative to the regulating wheel 21a, it is apparent that the grinding wheel 26 is mounted in predetermined relation to the outer surface of the workpiece and accordingly in predetermined relation to the axis of rotation of said workpiece, the axis of rotation being concentric to the cylindrical outer surface. With this arrangement the 20 wheel may be oscillated about its axis properly, to generate by transverse oscillation the correct 25 transverse curve in the individual peripheral race way. It will, of course, be understood that this generative action depends on a relative oscillation of the grinding wheel and work about the proper center, and if preferred can be effected by a movement of the work and its supporting and driving 30 unit, in place of the movement of the wheel, or in some instances the contour of the race way may be a direct contrageneric reproduction of the existing curve on the periphery of wheel 26.

35 From the foregoing, it will be apparent that the process involves the production of a multiplicity of concentric surfaces on a workpiece by simultaneously or successively grinding each of the concentric surfaces while the workpiece is 40 supported and rotated on a preformed cylindrical surface. The latter, may be formed as the first step in the process when the workpiece in its unfinished form is not already provided with such a cylindrical surface. It will be apparent 45 that the concentric surfaces may be cylindrical or conical, or the surfaces may extend radially as in finishing the parallel faces of the ball race shown, which surfaces, for accurate positioning of the ball race on the spindle 15, must be concentric to the cylindrical surface 13a and the 50 race ways 16 and 17.

We claim:

1. The process of producing a tubular article having concentric inner and outer surfaces, consisting in first forming a true cylindrical exterior surface thereon, rotating the article on said preformed surface while internally abrading same and effecting a relative axial translation between the work and abrading member to gen-

erate a true inner cylindrical bore, and similarly rotating the work piece on said preformed outer surface while restraining the same against axial movement, abrading a predetermined portion of said preformed outer surface to produce a 5 groove or depression therein, whereby said inner cylindrical surface and outer groove will be produced accurately concentric one to the other through use of the preformed outer surface as a position determinate during their formation. 10

2. The process of producing a tubular article having concentric inner and outer surfaces, consisting in first forming a true cylindrical exterior surface thereon, rotating the article on said preformed surface while internally abrading same 15 and effecting a relative axial translation between the work and abrading member to generate a true inner cylindrical bore, and similarly rotating the work piece on said preformed outer surface while restraining the same against axial movement, abrading a predetermined portion of 20 said preformed outer surface to produce a groove or depression therein, and effecting a relative oscillatory movement between the work piece and abrading member to generate the desired 25 form of groove therein, whereby said inner cylindrical surface and outer groove will be produced accurately concentric one to the other through use of the preformed outer surface as a position determinate during their formation. 30

3. The process of producing an accurate tubular article such as an inner ring or race for a ball bearing, consisting in initially forming the non-operative outer surface thereof to true cylindrical form by grinding in a centerless 35 grinder, supporting the work on its periphery by a work rest between grinding and regulating wheels, subsequently supporting and rotating the work by a rest and regulating member engaging the preformed outer periphery, abrading the inner surface thereof by an abrading member operating in opposition to the work piece supports to produce an inner surface in concentric relation to said preformed outer surface, similarly 40 supporting and rotating the work piece, restraining same against axial movement relative to its supports, abrading a selected portion of the outer periphery thereof during rotation, and effecting an oscillation between the work and its external abrading means to generate a peripheral groove 45 on the work, whereby said groove and inner surface of the work will be formed independent one to the other, but concentric each with the other, through utilization of the preformed non-operative outer surface as the common position determinate for the work during generation of the 50 subsequent surfaces. 55
